UNITED STATES PATENT OFFICE.

JULIUS JOHN MOJONNIER, OF OAK PARK, ILLINOIS, ASSIGNOR, BY MESNE ASSIGNMENTS, TO MOJONNIER BROS. CO., OF CHICAGO, ILLINOIS, A CORPORATION OF ILLINOIS.

COOLING CHAMBER.

Application filed April 15, 1916, Serial No. 91,404. Renewed December 21, 1922.

To all whom it may concern:

Be it known that I, JULIUS JOHN MOJONNIER, a citizen of the United States, residing at Oak Park, in the county of Cook and State of Illinois, have invented certain new and useful Improvements in Cooling Chambers, of which the following is a specification.

This invention relates to cooling chambers of the type designed to reduce the temperature of heated substances to the surrounding atmospheric temperature, having as an additional function the keeping of said substances thoroughly dry during the reduction of temperature thereof.

With the above and other objects in view, as will be apparent, this invention consists in the construction, combination and arrangement of parts, all as hereinafter more fully described, claimed and illustrated in the accompanying drawings wherein:

Figure 1 is a vertical longitudinal section taken adjacent to one side of a cooling chamber constructed in accordance with the present invention, illustrating the system of fluid circulation, whereby the fluid is maintained at atmospheric temperature.

Fig. 2 is a horizontal section taken along line 2—2 of Fig. 1, with parts broken away.

Fig. 3 is a vertical transverse section taken along line 3—3 of Fig. 1, showing the construction and mounting of the cooling or fluid circulation plate.

Fig. 4 is a perspective view of the cooling or fluid circulation plate.

In laboratories it is desirable and often essential, particularly where substances are weighed before and after heating, to reduce the temperature thereof after heating to that of the atmosphere, especially the atmosphere surrounding the balance; at the same time keeping the substance so cooled thoroughly dry. It is to accurately accomplish this that the present invention is designed, its principal function being to reduce the temperature of substances placed therein to the temperature of the atmosphere, while its incidental function is to keep said substances thoroughly dry during cooling, where such a result is desired or deemed necessary.

In carrying out the present invention a supporting frame F is provided, consisting of the base 10 and the uprights or standards 11. The upper ends of the uprights or standards 11 carry the frame piece 12 upon

which is mounted the cooling chamber C by means of the intermediate supports 13 extending from the frame piece 12 to the bottom of the cooling chamber C. The details of construction of the frame F, the frame piece 12, and the intermediate supports 13 form no part of the present invention, as they constitute, among other features, the subject-matter of a separate application.

The cooling chamber C comprises an elongated metallic casing 14, of a general rectangular construction, except at the entrance end thereof, which is obliquely arranged, as will be hereinafter more fully described. The entire casing is of substantially a solid construction, with the exception of the entrance or forward end, which is also closed by a door when the chamber is in operation. At its rear end 16, the casing 14 is provided with a transverse shoulder 15 formed from the end 16 adjacent to but removed from the bottom 17 of the casing. This shoulder 15 constitutes a support for the rear end of the cooling or circulation plate designated generally as P, so that it may be readily removed from the casing when desired. On each side of the bottom 17, at the forward or entrance end of the casing 14 and adjacent to the vertical side walls of said casing is a support or projection 18 of a height 85 equal to that of the shoulder 15. These supports 18 combine to support the forward end of the cooling or circulating plate P in a manner similar to the shoulder.

The cooling or circulation plate P is a 90 unitary rectangular structure made up of a series of abutting intercommunicating rectangular tubes 19, through which water or other cooling fluid is adapted to circulate. The tubes of the plate P are so arranged and held one against the other that when the plate is placed upon the shoulder 15 and the supports or projections 18, it constitutes what may be called a secondary bottom of the casing 14, resting parallel to and removed from the bottom 17 thereof, to create a chamber 20 thereunder.

To provide for the fluid circulation through the plate P, the side walls of the units, or tubes 19 thereof, are pierced by the 105 openings 21 adjacent to their ends, which when the tubes or units 19 are assembled so communicate that the fluid entering a tube must flow through the entire length thereof before it can pass into the next adjacent tube 110

or unit. That is, the opening 21, when the tubes 19 are assembled, are staggered, by having the openings 21 in one wall of a tube at one end thereof, and in the opposite wall at the other end of the same tube. Hence, when tubes 19 are assembled, every other pair of abutting side walls of the tubes 19 will have registering and intercommunicating openings at one end of the plate P; while the remaining abutting walls will have registering and intercommunicating openings at the other end of the plate. It is therefore apparent that the fluid enters one of the tubes 19, flows therethrough, enters the next adjacent tube and flows throughout the length thereof before passing to the next adjacent tube, and so the flow continues until the entire plate P has been traversed. Thus, throughout its entire length and breadth the plate P has a free circulation and flow of fluid designed to cool the plate and the contents of receptacles resting thereon.

At the rear end of one of the extreme side tubes 19 and in the underside thereof is an intake opening 22, to which is connected the pipe 23. This pipe 23 passes through the bottom 17 of the casing 14, as at 24, and is then coiled about the rear uprights or standards 11 of the frame F, extending from one standard or upright to the other, thereby creating the coil 25 exposed to the atmospheric temperature. The outer or free end 26 of the pipe 23 is connected to a source of fluid supply, by means of which a constant flow of fluid is maintained in the pipe 23, the coils 25 and the plate P.

The remaining extreme side tube 19 of the plate P opposed to the side tube having the intake opening 22, is provided in the under side thereof with a discharge connection 27, which likewise passes through the bottom 17 of the casing 14, as at 28, where it extends from under said casing and is provided with a faucet 29. By the provision of the faucet 29 the flow through the pipe 23 and plate P may be regulated, so as to adjust the temperature of the water flowing through the plate inside the chamber to atmospheric temperature.

It is manifest that the fluid flowing through the pipe 23 is brought to atmospheric temperature by the coil 25 before it enters the plate P, and that receptacles, together with their contents will, when placed on said plate, be likewise brought to the atmospheric temperature by the fluid flowing through the plate. Hence, whether the receptacles and their contents are above or below the atmospheric temperature when they are placed upon the plate P, their temperature is quickly brought to the atmospheric temperature by the flow and temperature of the fluid.

As has been pointed out, the entrance end

of the casing 14 is obliquely arranged, i. e., the bottom 17 thereof terminates beyond the top and the terminals of the side walls extend at an angle to the horizontal from the top to the bottom of the casing. This entire end of the casing is open and surrounded, on all sides by the outstanding flange or bead 30, which rests in the oblique plane of the entrance end of said casing. It is upon this flange or bead 30 that the door 31 of the casing 14 slides. The joint between the door 31 and the flange or bead 30 is ground to form an air-tight seal for the chamber when the door is closed. To provide for the reciprocation of the door 31 a guide rod 32 is secured to the top of the casing 14, by means of a bushing 33, and extends upwardly in a plane parallel to the entrance end of casing and to the plane of reciprocation of the door. Fixed medially to the upper edge of the door 31 is a bracket 34, which when said door is in its operative position, terminates adjacent to the bushing 33, where it is provided with a right angular, orificed extension 35. The orifice of the extension 35 receives the guide rod 32, so that said bracket 34 by means of its extensions 35 may reciprocate along said rod. The door 31 is provided with a knob 36, by means of which the door may be raised to move the bracket 34 and its extension 35 along the rod 32. After receptacles have been placed upon the plate P within the casing 14, the door is returned to its operative or closed position, where it rests flush upon the flange or bead 30; the weight of the door on said flange or bead practically sealing the entrance of the casing.

In the plane of the plate P is a platform 37, the utility, function, and construction of which forms no part hereof, from which the receptacles are moved to the casing 14, where they rest upon the plate P. To insure the ready passage of the receptacle from the platform 37 and the plate P, a transfer plate 38 is mounted on the studs 39 adjoining the forward end of the plate P and rests in the plane of both said plate P and the platform 37. The door when closed is positioned between the transfer plate 38 and the platform 37, and the space between the latter is only sufficient to permit of the reciprocation of said door.

An air exhausting pipe 40 communicates with the interior of the casing 14 through the bushing 41 in the bottom 17 thereof, and at its other end connects with a vacuum pump (not shown). Thus the air within the casing may be exhausted, if desired, which not only aids considerably in the cooling, but also prevents the substances cooling from being surrounded by moist air.

As a further precaution against the moisture within the casing 14 the chamber 20 under the plate P is provided, when desired, with the suitable receptacles 42, which may

contain drying agents such as calcium, chloride, potassium hydroxide, or sulphuric acid, all of which are absorbents of moisture.

The square tubular units of the plate P 5 may be secured one against the other in any desirable manner, but it has been found that subjecting the plate to a solder bath is the most effective and practical.

It will be clear from the foregoing that 10 the present invention can be used to operate upon substances the temperature of which is either below or above the temperature of the surrounding atmosphere, and in either event the temperature of said substances will 15 be made to conform to that of the atmosphere. It is also possible to circulate heated fluid through the pipe 23 and the circulation plate P, however, by applying heat to the coil or heating the fluid before it enters the 20 pipe 23. However, the present function is to reduce the temperature of heated substances to that of the surrounding atmosphere, and it is apparent that changes in the 25 details of construction in the present invention can be made without departing from the spirit and scope hereof.

What is claimed is:

1. An apparatus comprising a casing, enclosing supporting means for establishing a 30 fluid flow or circulation in combination with means for bringing said fluid to atmospheric temperature prior to its circulation as aforesaid.

2. The combination with a casing, of a 35 plate therein constructed of hollow intercommunicating units, intake and discharge connections communicating with the end units respectively, and a pipe coil co-operating 40 with said intake connection between said plate and a source of fluid supply for bringing said fluid to a predetermined temperature.

3. The combination with a casing, of a 45 plate therein constructed of a series of hollow, intercommunicating units, an intake connection communicating between the end one of said units and a source of fluid supply, and a pipe co-operating with said connection and provided with a coil exterior of said casing 50 and between said source of fluid supply and said plate for bringing said fluid to a predetermined temperature.

4. In a laboratory apparatus, the combination with a casing, of supports therefor, a 55 hollow shelf within said casing, means for circulating a fluid through said shelf, and

means carried by the supports aforesaid for regulating the temperature of said circulating fluid prior to its admission to and circulation through said shelf. 60

5. In a laboratory apparatus, the combination with a casing of a hollow shelf therein, means for circulating a fluid through said shelf, and means exterior of said casing for bringing the temperature of said fluid to the 65 temperature of the atmosphere surrounding said casing prior to the admission of said fluid into and its circulation through said shelf.

6. The combination with a casing, of a 70 plate supported therein in spaced relation from the bottom thereof, said plate being constructed of a series of hollow, rectangular units communicating one with the other directly through the walls thereof through 75 which a fluid is adapted to circulate laterally and lengthwise of said plate, an intake pipe connected with one side of said plate, and a discharge pipe connected with the opposite side of said plate, and a source of fluid supply 80 connected with said intake pipe.

7. The combination with a casing, of a 85 plate supported therein in spaced relation from the bottom thereof, said plate being constructed of a series of hollow, rectangular units communicating one with the other directly through the walls thereof through 90 which a fluid is adapted to circulate laterally and lengthwise of said plate, an intake pipe connected with one side of said plate, and a discharge pipe connected with the opposite side of said plate, a source of fluid supply 95 connected with the said intake pipe, and a coil in said intake pipe exterior of said casing and between said plate and said source of fluid supply.

8. The method of giving a predetermined temperature to material, which consists in placing the material on an enclosed support, 100 circulating a fluid through said support, and giving to said circulating fluid a predetermined temperature prior to its circulation.

9. The method of treating a material to give a predetermined temperature thereto and to dry it, which consists in placing the 105 material on an enclosed support, circulating a fluid through said support, giving to said fluid a predetermined temperature prior to its circulation, and placing a drying agent within the enclosure of said support.

JULIUS JOHN MOJONNIER.
